(57) **CLAIM**

We claim the ornamental design for an electronic device with adapter therefor, substantially as shown and described.

DESCRIPTION

FIG. 1 is a perspective view of an electronic device with adapter therefor according to the present design;

FIG. 2 is another perspective view thereof with the adapter removed for convenience of illustration;

FIG. 3 is an elevation of the side opposite that shown in FIG. 1 shown on an enlarged scale;

FIG. 4 is an elevation of the side opposite that shown in FIG. 3 with the adaptor removed for convenience of illustration;

FIG. 5 is an elevation of the side opposite that shown in FIG. 4;

FIG. 6 is a right side elevation thereof;

FIG. 7 is a left side elevation thereof;

FIG. 8 is another left side elevation thereof showing the adaptor connected;

FIG. 9 is a top plan view thereof;

FIG. 10 is another top plan view thereof showing the adaptor removed;

FIG. 11 is an end elevation with the broken lines used to represent environmental features;

FIG. 12 is a perspective view of the adapter member shown on an enlarged scale and removed from the electronic device;

FIG. 13 is a side elevation thereof;

FIG. 14 is a front elevation thereof; and,

FIG. 15 is a bottom plan view thereof.
